UNITED STATES PATENT OFFICE.

JOHN McLARTY, OF KLAMATH FALLS, OREGON.

SAWMILL APPLIANCE.

Application filed September 3, 1921. Serial No. 498,237.

To all whom it may concern:

Be it known that I, JOHN McLARTY, a citizen of the United States, residing at Klamath Falls, in the county of Klamath and State of Oregon, have invented new and useful Improvements in Sawmill Appliances, of which the following is a specification.

This invention relates to devices for use in saw mills, particularly to devices for handling the logs to be sawed, and has for its object the provision of a so-called nigger which is mounted overhead in contradistinction to certain types of niggers which operate from beneath, my device being power operated whereby to kick the logs onto the traveling carriage employed.

An important and more specific object is the provision of a device of this character which will have great strength and power, means being provided not only for swinging the device laterally but also for causing up and down movement of the log engaging member or nigger.

An additional object is the provision of a device of this character which will be simple and inexpensive in construction and installation, easy to operate, highly efficient in use, durable in service, and a general improvement in the art.

With the above and other objects and advantages in view, the invention consists in the details of construction to be hereinafter more fully described and claimed and illustrated in the accompanying drawings in which—

Figure 1 is a cross sectional view through a saw mill showing my device in one position,

Figure 2 is a similar view showing my device in operation and illustrating two different positions of the movable parts,

Figure 3 is a horizontal sectional view on the line 3—3 of Figure 1,

Figure 4 is a vertical sectional view on the line 4—4 of Figure 1,

Figure 5 is a detail view of one end of the upright cylinder.

Referring more particularly to the drawings, the letter A designates a portion of a frame of a saw mill which includes the usual floor B, uprights C, and cross beams D which support the roof E. The letter F designates the usual supports upon which are mounted the rails G upon which travel the usual carriage H which is adapted to trans-

port the logs I. The letter J designates the usual inclined table upon which the logs are placed prior to their disposition upon the carriage.

In carrying out my invention I provide a support including bars 10 secured in spaced relation below the bars D by means of suitable hangers 11. Secured upon the bars 10 are bearings 12 within which are journaled trunnions 13 extending from the sides of an elongated cylinder 14 within which operates a piston 15 carried by a piston rod 16.

Secured upon the bars D are bearings 17 within which are journaled trunnions 18 extending oppositely from a cylinder 19 within which operates a piston 20 carried by a piston rod 21. The numeral 22 designates the heads of the cylinder 19, these heads being formed with lateral extensions 23 which are provided with substantially I-shaped openings 24 through which is slid able an I beam 25 which is of considerably greater length than the cylinder 19. The free end of the piston rod 16 is pivotally connected with the extremity of the extension 23 at the lower end of the cylinder 19, as shown at 26. Secured upon the lower end of the I beam 25 is a foot 27 formed as a plate-like casting provided with spaced ears 28 which are secured to the free end of the piston rod 21. The lower surface of the plate or foot 27 is provided with a plurality of teeth 29 and secured to an edge of the lower end of the I beam are other teeth 30, all of these teeth being detachable so that they may be replaced when worn or broken.

The cylinders 14 and 19 are provided with inlets and exhausts designated by the numerals 31 and 32, respectively, the inlets being connected with a control valve 33 having an operating handle 34 and provided with a supply pipe 35 leading from any suitable compressed air or steam generating device. The arrangement of piping is the same as in the well known type of underneath nigger.

In the operation of the device it will be seen that when the control valve is manipulated to admit pressure to the cylinder 19 below the piston therein, the piston and rod 21 will be moved upwardly and this will also result in upward movement of the I beam 25 carrying the nigger foot 27. By manipulating the control valve to admit pressure rearwardly of the piston 15 in the

cylinder 14, the cylinder 19 and I beam 25 will be swung upon the trunnions 18 so that the beam and foot will be disposed above the logs I upon the table J. When pressure 5 is then admitted to the cylinder 19 above the piston therein, the I beam and foot will be forced downwardly into engagement with the log I nearest the carriage H. By then admitting pressure to the cylinder 14 in 10 front of the piston therein, it will be apparent that the cylinder 19 and I beam will be moved toward the carriage, dragging the log or turning it over and over to cause it to be disposed upon the carriage. Owing to the 15 pivotal mounting of both cylinders and the specific connections of the respective pistons with the foot and with the upright cylinder, it will be apparent that there will be perfect freedom of movement to permit all the 20 operations necessary in handling the logs in a very rapid and efficient manner.

While I have shown and described the preferred embodiment of my invention, it is of course to be understood that I reserve the 25 right to make such changes in the form, construction and arrangement of parts as will not depart from the spirit of the invention or the scope of the subjoined claims.

Having thus described my invention, I 30 claim:

1. A device of the character described comprising an elevated support, a cylinder pivoted thereon and provided with inlet and outlet ports, a piston operating within said cylinder and carrying a piston rod, a second elevated support, a cylinder pivoted on said second named support and provided with inlet and outlet ports, a piston operating within said second named cylinder and carrying 40 a piston rod, the first named piston rod being pivotally connected with the second named cylinder, means for supplying pressure into either or both of said cylinders at either side of the piston therein, and a log 45 engaging foot carried by the second named piston.

2. A device of the character described comprising an elevated support, a cylinder pivoted thereon and provided with inlet and 50 outlet ports, a piston operating within said cylinder and carrying a piston rod, a second elevated support, a cylinder pivoted on said second named support and provided with inlet and outlet ports, a piston operating within 55 said second named cylinder and carrying a piston rod, the first named piston rod being pivotally connected with the second named cylinder, means for supplying pressure into either or both of said cylinders at either side of the piston therein, a log 60 engaging

foot carried by the second named piston, and an I beam guidably slidable beside the second named cylinder and rigidly secured to said foot.

3. A device of the character described 65 comprising an elevated support, a cylinder pivoted thereon and provided with inlet and outlet ports, a piston operating within said cylinder and carrying a piston rod, a second elevated support, a cylinder pivoted on said second named support and provided with inlet and outlet ports, a piston operating within said second named cylinder and carrying a piston rod, the first named piston rod being pivotally connected with the second named cylinder, means for supplying pressure into either or both of said cylinders at either side of the piston therein, a log 70 engaging foot carried by the second named piston, an I beam guidably slidable beside the second named cylinder and rigidly secured to said foot, and a plurality of 75 removable teeth secured upon the underside of the foot and upon one edge of the beam at the lower end thereof.

4. A device of the character described 80 comprising an elevated support, a cylinder pivoted thereon and provided with inlet and outlet ports, a piston operating within said cylinder and carrying a piston rod, a second elevated support, a cylinder pivoted on said second named support and provided with inlet and outlet ports, a piston operating within said second named cylinder and carrying a piston rod, the first named piston rod being 85 pivotally connected with the second named cylinder, means for supplying pressure into either or both of said cylinders at either side of the piston therein, a beam 90 slidable along the second named cylinder and a log engaging foot carried by the beam and second named piston, said second named cylinder having its heads formed with lateral extensions provided with openings serving as 95 guides for said beam.

5. A device of the character described comprising a plurality of elevated supports, a pair of cylinders pivoted for swinging movement upon said supports, a piston within each cylinder and provided with a piston 100 rod, means for supplying pressure within either or both of said cylinders at either side of the pistons therein, one piston rod being connected with the other cylinder, a beam 105 slidable along one side of said other cylinder, guide means for said beam, and a toothed foot secured to said beam and connected with the other piston rod.

In testimony whereof I affix my signature.
JOHN McLARTY.
